DESIGN FOR A DRESS

Adele Smithline, Cos Cob, Conn.

Application September 27, 1940, Serial No. 95,460

Term of patent 3½ years

To all whom it may concern:

Be it known that I, Adele Smithline, a citizen of the United States, residing at Cat Rock Road, Cos Cob, in the county of Fairfield and State of Connecticut, have invented a new, original, and ornamental Design for a Dress, of which the following is a specification, reference being had to the accompanying drawing, forming part thereof.

the pockets and a part of the panel above the pocket, showing the trimming thereon.

The leather panels on the front of the dress, having slanting rows of braid separated by metal links and beads arranged thereon as shown, are bordered on each side by a row of nailheads and terminate on the pocket members in a tassel which is interspersed with metal links.

I claim:

The ornamental design for a dress, substantially as shown and described.

ADELE SMITHLINE.
